UNITED STATES PATENT OFFICE.

CECIL HAMELIN TAYLOR AND BOUDEWIJN B. NEUTEBOOM, OF DETROIT, MICHIGAN.

CASTING V INTERNAL-COMBUSTION ENGINES.

1,274,105.

Specification of Letters Patent. Patented July 30, 1918.

Application filed November 25, 1912. Serial No. 733,291.

To all whom it may concern:

Be it known that we, CECIL HAMELIN TAYLOR, a citizen of the United States, and BOUDEWIJN B. NEUTEBOOM, a subject of the Queen of the Netherlands, residing at Detroit, county of Wayne, State of Michigan, have invented a certain new and useful Improvement in Castings for Internal-Combustion Engines, and declare the following to be a full, clear, and exact description of the same, such as will enable others skilled in the art to which it pertains to make and use the same, reference being had to the accompanying drawings, which form a part of this specification.

Our invention relates to internal combustion engines and a special object of our improvements is to provide an improved lubricating system.

20 In the accompanying drawings:

Figure 1, is a sectional elevation of a portion of a gas engine embodying our invention.

Fig. 2, is a sectional plan view, the section being taken on the line B—B Figs. 1, 5 and 6.

Fig. 3, is a plan view of the parts shown in Fig. 1, the top or cover being removed,

Fig. 4, is a section in the plane indicated by the line D—D Figs. 2, 3 and 5.

Fig. 5, is an elevation of the upper end of the part shown in Figs. 1 and 3.

Fig. 6, is a section on the line F—F Fig. 9 looking from the left of said line.

35 Fig. 7 is a section of the mold in which the casting forming the body of the engine is made showing the cores in place.

Fig. 8, is a detail sectional view on the line H—H Fig. 7.

40 Fig. 9, is a plan view of the part shown in Fig. 7, the upper portion of the mold being removed.

a is the casting forming the body of major portion of the engine. b is the cover or top which is formed separate from the body a and is secured in place to close the upper end of the cylinders and passages. c is a reservoir for lubricating oil secured at the bottom of the casting a. 2 is the crank case. d is a bearing for the main shaft of the engine. g is the valve actuating counter shaft. e and f are the gear wheels through which the motion from the main shaft is conveyed to the counter shaft g. The 55 counter shaft g and the gear wheels e f are located in the crank case and the bearing d

in the wall thereof. h h are push rods by which the valve stems are actuated. i is a chamber formed toward the center of the casting a and extending longitudinally thereof adapted to contain lubricating oil. j is a partition extending upward from the bottom and into the reservoir i adapted to prevent the oil from flowing in too large quantities toward one end of said reservoir 60 when it is tilted.

k is a conduit leading from the bearing d to the reservoir i and extending over the gear wheel f. l is an over-flow pipe. 3^a 3^a is the crank shaft located in the casing 70 2 and resting in part in the bearing d. The pipe l is opened at its lower end to the reservoir c and extends a short distance up into the crank case 2 so that oil accumulating in the crank case shall flow back through 75 the pipe l into the reservoir c. m is a small aperture formed through a wall or conduit k just above the gear wheel f so that a small portion of oil flowing through the conduit will drop upon the gear wheel f and be there- 80 by conveyed to the gear wheel e. The gear wheels e and f are located in the crank case 2 so that any excess of oil will flow into said crank case.

n (Fig. 4) is a pipe leading to the reservoir i at its upper end and communicating with passages which open through a pipe z beneath the level of the oil in the reservoir c. o is a non-return valve opening toward the reservoir i in the passage between said reservoir and the reservoir c. p is a similar valve also located in the passages forming a communication between said reservoirs. q is a plunger between the valves o and p, by the reciprocation of which oil is drawn from 90 the reservoir c and forced through the pipe n into the reservoir i. r is a cam upon the counter shaft g which cam acts to actuate the plunger q in a well known manner.

s is a small conduit in the casting a, opening at its upper end to the reservoir i and having its lower end above the cam r. Oil runs through the conduit s and drops upon said cam the excess flowing into the crank case 2. t is a conduit similar to s having 100 its upper end opening into the reservoir i and its lower end opening into a cup-like receptacle u above one of the intermediate bearings v for the main shaft of the engine. v (Fig. 6) indicates one of the connecting 110 rods of the engine which is pivoted to a piston 8 in a cylinder 7.

2
 2 is an aperture formed in the bottom of the reservoir *i* so that the oil passing therethrough by gravity shall drop upon the lower end of the connecting rod *y* and form a lubrication therefor. 30, 30 are the exhaust ports, and 31, 31 the intake ports, these are located in line with each other.

3, 3 indicate water passages forming parts of the water jacket or the cylinder 7, 7, 7 10 formed in the casting *a*. 4, indicates one of the exhaust passages of which there are two entirely similar located at opposite ends of the casting *a*, and extending in the same plane longitudinally of the casting. 5, indicates the intake passage. This has two branches extending in opposite directions and located approximately in the plane of the exhaust passages 4, and also extending longitudinally of the casting. The passages 15 20 4 and 5 extend upon opposite sides of the line of valves and are offset to accommodate their appropriate valves.

9, is an opening to the water jacket in the casting *a*. 34 indicate the ports to the intake and exhaust valves. 10 is a passage leading upward from the reservoir *i* opening at the top of the casting *a* through which the reservoir *i* may be filled. 11, is a cap adapted to close the upper end of the passage 10. 12, (Fig. 1) is an intermediate bearing for the counter shaft *g*. 13, is a conduit opening at its upper end to the reservoir *i* and at its lower end to the bearing 12 so as to supply lubricating oil to said bearing.

35 14 (Fig. 4) is a passage opening to the crank case 2 at its lower end and at its upper end to the reservoir *i* above the normal level of the oil in said reservoir. The passage 14 serves as an over-flow to prevent too great an accumulation of oil in the reservoir *i*.

The casting *a* is formed in the four-part mold of which the divisions are indicated by the reference figures 15, 16, 17 and 18 in Fig. 7.

45 19, is the core for the cylinders and crank case. 20, and 23 are the cores for the water passages of the water jackets. The core 20 is secured in place by the core prints 20^p, 20^p resting in the sections 16 of the mold and 50 by core prints 20^{p2}, 20^{p2} also resting in said sections of the mold. The core prints 20^p and 20^{p2} are so located that they shall form the passages for the water to and from the water jacket 3.

55 The core 23 rests upon and is supported by the core 20. 21 and 21^a are corresponding cores adapted to form the exhaust passages 4. These are supported in place by the core prints 21^p, 21^p which extend laterally and 60 are supported by the core part 16. The prints 21^p are so located as to form the exit opening from the passages 21 and 21^a. 21^{p2}, 21^{p2} are vertically extending core prints reaching from the cores 21, 21^a. These extend into and are supported by the upper

section 15 of the mold and are so located as to form the opening above the ports for the exhaust valves. 22, is a core adapted to form the intake pipe 5, this is supported by a laterally extending core print 22^p and by 70 vertically extending core prints 22^{p2}. The mold is divided between the sections 17 and 18 at the larger part of the crank case as indicated at Fig. 7 and between the parts 17 and 18 intermediate the portions of the mold 75 25, 26 which form the oil reservoir *i*, the portion 25 being on the part 17 and the portion 26 on the part 16. Said mold is again divided in a line at approximately the center of the portions forming the inlet and exhaust passages 4 and 5.

By the above arrangement of the mold and pattern the patterns can be firmly held in place and readily adjusted to position.

The casting *a* may be cheaply and accurately made and forms a convenient construction adapted to constitute a portion of an internal combustion engine and which may be readily assembled and when so assembled it will afford a sufficient system of lubrication.

The reciprocation of the plunger *q* during the operation of the engine continually throws oil from the reservoir *e* and forces it into the reservoir *i* from which it is distributed by the various passages above described and in other well known ways to the various parts requiring lubrication. The push rods *h* *h* *h* extend into the reservoir *i* and are lubricated by the oil therein. The small contacting ends of the push rods and valve stems permit a free movement of oil therebetween except that a film of oil will adhere to the contacting surfaces and cushion the impact between the two surfaces.

What we claim is:—

1. In an internal combustion engine, a crank case, a reservoir located above said crank case, a reservoir located at the lower portion of said crank case, a main shaft located within said crank case and having bearings in the walls thereof, a cam shaft located in bearings in said crank case, gear wheels connecting said shafts, push rods 110 adapted to actuate the valves extending through the bottom of said upper reservoir in position to be actuated by the cams on the cam shaft, and conduits for oil leading from said upper reservoir to the parts of said 115 mechanism requiring lubrication.

2. In an internal combustion engine, a valve a reservoir for lubricating oil located below said valve, said valve having a stem extending into said reservoir beneath the 120 level of oil therein, and a push rod extending through the wall of said reservoir beneath the level of the oil therein, and adapted to actuate said valve stem.

3. In an internal combustion engine, an 125

upper and a lower reservoir for lubricating oil, valves for said engine, said valves extending in part below the surface of the oil in said upper reservoir, and means for circulating the oil between said reservoirs.

4. In an internal combustion engine, an upper and a lower reservoir for lubricating oil, means for circulating oil between said reservoirs and a valve actuating rod extending through the wall of said upper reservoir beneath the level of the oil therein.

5. In an internal combustion engine of the puppet valve type, the combination with a valve stem, of a relatively reciprocable valve operating member, and an oil containing casing surrounding the joint between said stem and member, whereby said joint may be submerged in liquid, the contacting surfaces of said stem and valve operating member permitting free movement of the oil between the contacting surfaces except for the adhesion of the oil thereto.

6. In an internal combustion engine, the combination, with cylinders and reciprocable

valves for said cylinders, said valves having stems, of reciprocable valve operating members supported in alinement with the valve stems independently thereof, cams for operating said members, and containers surrounding the point of contact between each operating member and its valve stem, whereby the ends of said members may be kept submerged in liquid.

7. In an internal combustion engine of the puppet valve type, the combination with a valve stem, of a relatively reciprocable jump rod sleeved in alinement therewith, and an oil containing casing surrounding the joint between said stem and rod, whereby said joint may be submerged in liquid.

In testimony whereof we sign this specification in the presence of two witnesses.

CECIL HAMELIN TAYLOR.
BOUDEWIJN B. NEUTEBOOM.
